D7-137. OR D 11,728 EX

No. 11,728

April 13, 1880

UNITED STATES PATENT OFFICE.

CHARLES T. GROSJEAN, OF GREEN POINT, ASSIGNOR TO TIFFANY & CO.,
OF NEW YORK, N. Y.

DESIGN FOR SPOON OR FORK HANDLE.

SPECIFICATION forming part of Design No. 11,728, dated April 13, 1880.

Application filed March 20, 1880. Term of patent 14 years.

To all whom it may concern:

Be it known that I, CHARLES T. GROSJEAN, a citizen of the United States, residing at Green Point, in the county of Kings and State of New York, have invented and produced a new and original Design for a Spoon or Fork Handle, of which the following is a specification, reference being had to the accompanying drawings, forming part thereof.

10 The features of novelty in this design of spoon or fork handle consist—

First, in an irregular or wavy outline of the handle of the spoon or fork, presenting the appearance of a series of depressions on such 15 outline.

Second, in an irregular or wavy edge running around the front surface of the handle.

Third, in a depression on the back of the handle running its whole length, or nearly so, 20 and which widens or loses itself in the outline, which outline continues a smooth but raised rounded edge lapped over onto the front, and ending on such front in a wavy edge. This wavy edge extends all around the front to the 25 points where it joins the bowl of the spoon or the shoulder of the fork.

These features may be used on spoon and fork handles unlike in other respects—as, for instance, Figures 1 and 2 are different in form 30 from Figs. 3 and 4, yet embody all the features of this design.

In these figures, *a* is the irregular or wavy form of the outline of the handle. *b* is the depression running the whole length of the back. *c* is the raised rounded edge lapping over onto 35 the front surface. *d* is the wavy edge of the raised rounded edge extending all around on the front to the points where it joins the bowl of the spoon or the shoulder of the fork.

Spoons or forks differing in their general 40 contour may be manufactured with one or more of these features, so as to contain the same character or family resemblance, so far as my invention is concerned.

I claim—

1. The wavy outline *a* of the spoon or fork handle, substantially as described.

2. The wavy edge *d* of the raised rounded edge *c* of the outline, extending around on the front surface of the spoon or fork handle, substantially as described.

3. The wavy edge *d* of the raised rounded edge *c* of the outline lapping over onto the front surface, together with a depression in the back surface running the whole length, or 55 nearly so, of the back of the spoon or fork, substantially as described.

CHAS. T. GROSJEAN.
